WINDOW FASTENER

Filed Feb. 4, 1929

FRANCES KEATING Inventor

By *Herbert E. Smith*.

Attorney

UNITED STATES PATENT OFFICE

FRANCES KEATING, OF SPOKANE, WASHINGTON

WINDOW FASTENER

Application filed February 4, 1929. Serial No. 337,447.

My present invention relates to improvements in window fasteners of the type especially designed for use with the upper and lower sashes of the ordinary slide windows. The primary object of the invention is the provision of fastening devices that are capable of locking the sashes in closed position, or in partly opened positions for ventilating a room, and at the same time insure against intrusion from the exterior of a room and prevent access to the fasteners by unauthorized persons. To these ends the fasteners for the two sashes comprise guide rods secured rigidly on and movable with the sashes, and a stationary housing with spring pressed, automatically operating latches or pawls for co-action with the rods, together with releasing means involving the use of a key, whereby the sashes may be unfastened from the interior of a room. The invention consists in certain novel combinations and arrangements of parts involving the fasteners and their releasing devices as will herein-after be more fully set forth and claimed.

In the accompanying drawings I have illustrated one complete example of the physical embodiment of my invention wherein the parts are combined and arranged according to the best mode I have thus far devised for the practical application of the principles of my invention.

Figure 1 is a broken, perspective view showing the window fastener with a key therein, and showing also the relation of the guide rods and sashes to the fastening devices.

Figure 2 is a view of the lock-housing with the cover plate removed showing the operating parts in its interior.

Figure 3 is a view in elevation, from the interior of a room, showing the window fastener in use with both sashes closed.

Figure 4 is a perspective view of one of the spreader or spacing blocks, forming the key-guard, and located in the casing or housing for the operating parts of the fastener.

In order that the general arrangement and relation of parts may readily be understood I have illustrated the usual rectangular window frame 1 with the upper and lower sliding sashes 2 and 3 respectively. The fasten-

ing devices are located at the inner side of the window, and are accessible only from the interior of the room.

The upper sash is provided with a vertically arranged guide rod 4 which has a top angular bar 5 that is fastened at 6 rigidly to the upper sash, in such manner as to space the vertical rod a slight distance from the sash. At suitable intervals a plurality of notches 7 are fashioned in the rod, and it will be understood that the rigidly attached rod moves with the sash when it is lowered or raised.

The lower sash also has a guide rod, as 8, fashioned with a bottom angular bar 9 that is secured at 9' to the lower end of the lower sash, and this rod has spaced notches 10 similar to the notches 7.

On the window frame, about midway its height, I attach the metal casing 11, which has attaching flanges 12 at its top and bottom, and these flanges are secured by screws 13 to the window frame 1.

The casing as shown is fashioned with top and bottom plates 14 perforated to receive the free ends of the upper rod 4 and the lower rod 8, the rods at all times being located in the perforated walls and guided, as they are moved with their respective sashes, by the pair of spaced guide plates 14. Thus the sashes, in Figure 1 are fastened in closed position with both ends of the rods secured in the perforated guide walls or plates of the casing, and it will be understood that the upper sash may be lowered, and the lower sash raised, to desired positions, as for ventilation, and there locked in connection with the guide rods.

The fastening devices that co-act with the rods, are of complementary construction, but they are operated and arranged in reversed positions. Thus, for co-action with the notches of the upper rod I provide a pawl or latch 15, pivoted at 16 within the casing, and a spring 17 bearing against the pawl normally holds the free end of the pawl against the rod so that it will automatically engage in one of the notches 7.

For the lower rod a pawl or latch 18 is pivoted at 19 in the casing, and a spring 20

bears against this pawl to normally hold it against the rod 8 and in position to engage in a notch 10.

At one end, both of the springs or resilient blades 17 and 18 are anchored, as by a stud 21, in the housing or casing, and as shown in Figure 2 the springs urge the respective pawls in opposite directions for proper co-action with the notched rods.

10 At the left side of the casing, in Figure 3, a removable cover plate 22 is secured on the casing, as by screws 23, and access to the interior of the casing is had at this left side.

The cover plate and the main plate of the 15 casing are slotted or slitted, and between these slotted or slotted members a pair of blocks 24 and 25 are located, said blocks having attaching lugs or flanges 26 at their opposite ends that are clinched in the slits or slots 20 of the cover plate and main or base plate of the casing.

These blocks form key-guards and they are each provided with a key-hole slot 27, which registers with a complementary hole 27' in 25 the cover plate, and an open mortise 28 at one side of the slot, as best seen in Figure 4.

A key 29 is designed to be inserted in either of the key-hole slots of the guards, and when its angular head is positioned adjacent the 30 mortise 28, it will be apparent that a turn of the key in its guard brings the head of the key into frictional contact with the spring 35 pressed pawl, 15 or 18. A continued turn of the key forces the pawl out of engagement with the notch in the guide rod, and the window sash and rod are then free to be moved to desired position, until the pawl again engages a notch, at which time the sash is held stationary. When the key is withdrawn, the 40 spring automatically returns the pawl to position for engagement with a notch.

In Figure 2 another type of releasing device is illustrated, where the pawl 30 is turned or freed against the tension of the spring 45 31, by turning a shank 32 that is supported to turn in the cover plate and base plate of the casing. This shank has an eccentric or cam shaped head 33 within the casing in position to frictionally engage the pawl 30, and a 50 knob 34 on the shank, exterior of the casing may be used to turn the shank, for releasing the pawl from the notch.

Having thus fully described my invention, what I claim as new and desire to secure by 55 Letters Patent is:—

1. The combination with a slidable sash having a notched guide rod, of a stationary casing having spaced perforated walls for said rod, a spring pressed pawl pivoted with- 60 in the casing to engage the notched rod, a key-guard within the casing adjacent the pawl, and said guard having a key-hole slot and mortise to accommodate a headed-key.

2. The combination with a slidable sash having a notched guide rod, of a stationary 65

casing having spaced perforated guide walls for the rod, a pivoted pawl within the casing for engagement with the notched rod, a spring anchored in the casing and normally holding the pawl in position for engagement with the notched rod, a key-guard secured in the casing and adapted to receive a headed-key, and said guard having a key-hole slot and mortise opening adjacent the pawl.

In testimony whereof I affix my signature. 75
